PARTS TREATING MACHINE

Thomas W. Jackson, Thornhill, Ontario, Canada, assignor to G. S. Blakeslee & Co., Chicago, Ill., a corporation of Illinois

Filed Oct. 29, 1958, Ser. No. 770,521

3 Claims. (Cl. 259—3)

This invention relates to machines for treating parts by tumbling during washing, pickling, coating, drying or other treatment, to assure contact of the treating liquid or fluid with all of the parts under treatment.

It is known to treat machine parts and various other articles by tumbling in a rotating drum or cylinder having openings or perforations for discharge of the treating liquid or fluid. The parts so treated are usually of appreciable size and free of points or small projections, such that they will not become caught in the perforations or openings of the cylinder and cause objectionable clogging thereof with resultant slowing down or interference with the treating operation. In treating small parts, particularly small nails, screws, tacks and other small pointed parts, difficulty is encountered due to the fact that such parts enter the openings or perforations in the treating cylinder and quickly clog it to such extent as to either completely prevent, or seriously interfere with, travel through the cylinder of the articles under treatment. The same difficulty is encountered in treating larger parts having points or small projections which can enter the openings or perforations of the treating drum or cylinder. For that reason it has not been practicable to treat parts of the character referred to in bulk in rotating cylinders having openings or perforations for discharge of the treating liquid or fluid and, so far as I am aware, that has never been satisfactorily and successfully accomplished.

My invention is directed to a machine which avoids the difficulties above mentioned in respect to the presently known treating machines above referred to and renders possible satisfactory treatment in bulk of parts of the character stated, in a rotating drum or cylinder having perforations or openings for discharge of the treating liquid or fluid. To that end I provide a rotating drum or cylinder having selected areas thereof provided with openings or perforations, such areas being shielded by means effectively guarding against small parts, or small points or projections of larger parts, entering the openings or perforations while assuring ready flow therethrough of the treating liquid or fluid. More specifically, the perforated areas of the cylinder wall are shielded by baffles overlying such areas and spaced inwardly therefrom, the baffles providing in conjunction with the cylinder wall spaces opening into the cylinder at their following sides and being otherwise closed to the cylinder. The baffles provide effective reinforcement for the cylinder structure and preferably, though not necessarily, are provided with stiffening and reinforcing elements which also function as deflectors for agitating the articles under treatment to assure contact therewith of the treating liquid or fluid. The machine of my invention will be described as used for washing small parts, by way of example only, though it may be used for various other purposes, as above noted. Further objects and advantages of my invention will appear from the detail description.

In the drawings:

Figure 1 is a side view of a parts treating machine embodying my invention;

Figure 2 is an end view of the machine of Figure 1, as seen from the discharge end;

2

Figure 3 is a plan view, on an enlarged scale, of the discharge end portion of the treating cylinder structure of the machine of Figure 1;

Figure 4 is a sectional view, on an enlarged scale, taken substantially on line 4—4 of Figure 3;

Figure 5 is a sectional view taken substantially on line 5—5 of Figure 4; and

Figure 6 is a sectional view similar to Figure 5 but showing a modified form of my invention.

The machine shown in Figures 1 and 2 is, in general, of known construction, except as to the parts thereof having to do particularly with my invention, and a brief description thereof will suffice. It comprises a suitable housing 10 the lower portion of which constitutes a tank 15 for receiving a washing solution or other liquid used in treatment of the parts, as will be explained more fully later. A two compartment tank 11 is provided at one side of housing 10 and includes a tank 12 for a washing solution and a tank 13 for a rinsing solution or liquid, the tanks 12 and 13 being separated by a partition 14. The housing 10 is provided with a removable top or cover 15 of arcuate cross section which overlies a treating cylinder 16 extending lengthwise of housing 10 and disposed above the tank in the lower portion of the housing. The cylinder 16 is shown as disposed horizontally lengthwise, though it may be disposed in any suitable position, and is rotatably supported in a suitable manner. Conveniently the cylinder is rotatably supported by rollers 17 mounted in brackets 18 secured to frame members of housing 10, the rollers being disposed adjacent each end of cylinder 16 and receiving appropriately formed tires or bands 19 secured on cylinder 16 exteriorly thereof. It will be understood that cylinder 16 may be rotatably supported at intermediate points, if desired or necessary, and may be rotatably supported in any suitable manner. The parts to be treated are delivered to the feed end of the cylinder in any suitable manner, conveniently by means of a suitable hopper 20 and, during rotation of cylinder 16 in one direction, are propelled therethrough by means of a helical strip 21 secured interiorly of cylinder 16, to the other or discharge end at which the treated articles may be discharged into suitable receptacles or onto a conveyor, as is known. The cylinder 16 is rotated in proper direction and at moderate speed by a chain 22 which passes about a sprocket ring 23 secured about cylinder 16 adjacent the discharge end thereof and passing about a sprocket 24 secured on the output shaft 25 of a speed reducer unit 26 of suitable known type the input shaft of which is driven by an electric motor 27 by means of a V belt and pulley drive 28. As will be understood, the cylinder 16 may be driven in any suitable manner. As is shown in the drawings, the helical strip 21 is continuous and seats on the inner face of cylinder 16 for the full circumference thereof, to which it is secured in any suitable manner, conveniently by welding. That effectively eliminates possibility of jamming of articles under treatment between the strip 21 and the cylinder wall and expedites flow of the articles through the cylinder, conducive to large capacity and smooth operation. The width of the helical strip 21 is considerably less than the radius of cylinder 16 leaving an unobstructed cylindrical opening of substantial diameter extending from end to end of the cylinder. A washing fluid spray pipe 29 extends into cylinder 16 from the feed end thereof and is provided, for approximately two-fifths of its length within cylinder 16, with suitably disposed spray openings or perforations. A rinsing fluid spray pipe 30 extends into cylinder 16 through the discharge end thereof and is provided, with a plurality of suitably disposed spray openings or perforations, it being noted that the spray pipe 30 is of consider-

ably greater length than the spray pipe 29, the perforated area of each of the pipes being located at the inner portion thereof.

It may be assumed, for purposes of description, that the machine is used for washing small parts, such as nails, for example, which may be coated with oil or grease with adhering small particles of metal cuttings. The tank 12 contains an alkaline washing solution which is withdrawn therefrom and delivered to the spray pipe 29, under appropriate pressure, by a pump 31 driven by an electric motor 32. The rinse liquid, which may be either a suitable solution, or clear water, is withdrawn from tank 13 and delivered to spray pipe 30 under appropriate pressure, by means of a pump 33 driven by an electric motor 34. The parts are washed in the first section of the cylinder and are rinsed in the succeeding section thereof, the wash and rinse liquid passing through openings in cylinder 16 into the tank in the lower portion of housing 10. The section of cylinder 16 beyond the rinse spray area is a drying section in which the liquid is drained from the articles and they are dried by their own heat, it being understood that the washing solution and the spray liquid may be heated to a comparatively high temperature. If desired, heated air may be delivered to the cylinder 16 through the discharge end thereof, by means of a suitably located conduit, as is known. The construction and operation of the machine so far described is, in general, known. Such known machines are not suitable for treating small parts such as nails and analogous parts previously referred to, or larger parts having points or small projections such as would enter the perforations or openings in the cylinder wall, the primary object of my invention being to provide a machine suitable for treating such parts in bulk, as previously stated.

In washing machines of the type above described, the cylinder is perforated throughout its full circumference for discharge therefrom of the treating fluid or liquid, and is not provided with means preventing entry of points or small projections of the parts under treatment into the cylinder openings or perforations. Such machines are not suitable for treating small parts, or larger parts having points or small projections, as and for the reasons above pointed out. In the machine of my invention selected areas only of the cylinder are perforated and such areas are guarded in a manner to eliminate possibility of small parts, or points or small projections of larger parts, under treatment entering the perforations of the cylinder while assuring free discharge therefrom of the treating liquid or fluid. As has been indicated, my invention has to do particularly with the structure of the cylinder for treating parts of the character previously mentioned. Referring to Figures 3, 4 and 5, I provide a cylinder structure comprising the cylinder 16 within which is secured the helical strip 21 of considerably less width than the radius of cylinder 16, strip 21 being suitably secured to the inner face of the cylinder wall, conveniently by welding. The cylinder wall is provided with substantially rectangular perforated areas 38 spaced apart circumferentially thereof by intervening imperforate areas 46 and each constituting a segment of the circumference of cylinder 16, each of the imperforate areas also constituting a segment of the circumference of cylinder 16 and having a smooth and unobstructed inner surface. Each of the perforated areas 38 is of substantial extent both lengthwise and circumferentially of cylinder 16, includes a plurality of perforations, and is guarded by a baffle member 39 which, like the corresponding perforated area 38, is of approximately rectangular shape in plan and is substantially coextensive with perforated area 38. The baffle member 39 is spaced inwardly of the cylinder 16 radially thereof from and in proximity to the perforated area 38 and extends from one convolution of the strip 21 to the next adjacent convolution thereof the ends of baffle 39 being secured, conveniently by welding,

to the convolutions of strip 21. The baffles 39 reinforce the strip 21 and, in cooperation with the latter, reinforce the wall of cylinder 16. The cylinder 16 is rotated at moderate speed counter-clockwise, as viewed in Figure 4 and indicated by the arrow 40, in the manner previously described in respect to Figures 1 and 2. Each of the baffle members 39 is preferably, though not necessarily, provided at the leading side thereof with a lengthwise rib 41 of substantially rounded V cross section extending radially inward of cylinder 16 beyond the main or body portion of baffle member 39, the leading arm or wall of member 39 extending to the wall of cylinder 16, at the leading side of the perforated area 38, and being secured to the cylinder wall in a suitable manner, conveniently by being welded thereto at 42. The baffle member 39 defines, in cooperation with the corresponding convolutions of strip 21 and the perforated area 38 of the wall of cylinder 16, a space 43 which opens at its following side, at 44, into the interior of cylinder 16 and is otherwise closed thereto. During rotation of the cylinder structure, the baffles 39 effectively guard against access of the small parts under treatment to the perforated areas of the cylinder wall and the spaces 43 opening at their following sides into the cylinder assure discharge therefrom, through the perforated areas 38, of the treating fluid or liquid. During rotation of the cylinder structure the nails or other parts under treatment seek the lower portion of the cylinder and are directed inward radially thereof by the ribs 41, over which the parts flow onto the main portion or body of the respective baffle members 39, so as to be effectively tumbled and agitated in a manner assuring that all of the parts under treatment will be exposed to the treating fluid or liquid, as will be understood from Figure 4 in which the deflecting and tumbling of the nails by the ribs 41 is indicated. The baffle members 39 effectively guard against access of the parts under treatment to the perforated areas of the cylinder wall, thereby effectively assuring that such parts cannot enter the perforations of such areas, and do not interfere to any objectionable extent with discharge from the cylinder structure of the treating fluid or liquid. The baffle members 39 also effectively reinforce the cylinder structure, the ribs 41 imparting desirable rigidity to the baffle members and additional mechanical strength while also functioning as means for imparting desirable agitation and tumbling to the parts under treatment, as above explained. When the machine is used for treating small parts, as above described by way of example, the perforations of the spray pipes 29 and 30 preferably are directed substantially horizontally toward the upwardly travelling side of the cylinder to wash from the members 39, toward the following edges thereof, any of the small articles which may adhere to baffle members 39.

In the form of cylinder structure shown in Figures 3, 4 and 5, the perforated areas 38 of the cylinder wall may be continuous lengthwise thereof and across the radially outer edges of a plurality of convolutions of the strip 21, as shown in Figure 3. In the modified form of cylinder structure shown in Figure 6, the wall of cylinder 16a is provided with perforated areas 38a of less length than the distance between two adjacent convolutions of the helical strip 21 and the baffle members 39a are provided with end walls 39b extending to the cylinder wall and secured thereto, conveniently by welding, at the ends of the perforated areas 38a. The baffle members 39a are provided at their leading sides with ribs 41a, as before, the leading arms of which are welded to the cylinder wall at 42a. The baffle members 39a provide, in cooperation with the perforated areas 38a of the cylinder wall spaces 43a opening at their following sides, at 44a, into the interior of the cylinder 16a and otherwise closed thereto. The operation of the machine embodying the modified form of cylinder structure shown in Figure 6, is essentially the same as that of the machine embodying the cylinder structure shown in Figures

3, 4 and 5, and need not be described in greater detail. In either case the baffle members effectively prevent access of small parts being treated to the perforated areas of the cylinder wall, thereby guarding against possibility of such parts entering or becoming caught in the perforations of the cylinder wall, while assuring the discharge from the cylinder of the treating fluid or liquid in adequate volume.

Preferably, the baffle members 39 and 39a are disposed concentrically with the cylinder wall, as shown, so as not to obstruct the interior of the cylinder to appreciable extent, though they may be disposed in any other suitable manner, within the broader concept of my invention.

I have described the machine of my invention as used for washing small parts, by way of example, but it is also well suited for otherwise treating either small parts or larger parts of a character such that they might become caught in the cylinder openings or perforations of the previously known machines. If desired the cylinder 16 may be used throughout its length for subjecting the parts to one treatment only, the articles treated in cylinder 16 being subjected, if desired, to further treatment in separate apparatus. It will be understood that the perforations of the spray pipes, when used, may be suitably disposed in accordance with the parts under treatment. In treating certain parts the ribs 41 or 41a of the baffle members 39 or 39a may be omitted, as indicated above, and, if used may be formed to act to best advantage on the articles under treatment. As indicated, instead of the spray pipes 29 and 30 any suitable means may be provided for supplying to the cylinder 16 any suitable liquid or fluid for treatment of the articles.

In both forms of cylinder shown the perforated areas are of substantial extent both lengthwise and circumferentially of the cylinder and respectively include a large number of perforations, the baffle members are concentric with and in proximity to the perforated areas, and the imperforate areas have smooth and unobstructed inner surfaces. Accordingly, during rotation of the cylinder, the parts under treatment are agitated sufficiently for effecting the desired treatment and objectionably violent agitation of the articles, such as might cause entry of substantial numbers of the articles between the baffles and perforated areas of the cylinder, is avoided. Due to the fact that the perforated areas are of substantial extent, the individual perforations may be quite small, obviating escape therethrough of any articles which may enter the space between a baffle member and a perforated area while providing for ready flow of the treating fluid through the perforated areas.

It will be understood that changes in detail may be resorted to without departing from the field and scope of my invention, and I intend to include all such variations, as fall within the scope of the appended claims, in this application in which the preferred forms only of my invention have been disclosed.

I claim:

1. In a parts treating machine, a rotatably mounted cylinder having a feed end and a discharge end open for discharge of the treated articles, means for rotating said cylinder in one direction, a continuous helical strip seating on and secured to the inner face of said cylinder for the full circumference thereof and disposed to propel articles under treatment toward the discharge end of said cylinder during rotation thereof in said one direction, the wall of said cylinder being provided with perforated areas spaced apart circumferentially thereof, means for supplying treating fluid to said cylinder, and imperforate baffle members secured to the inner face of said cylinder disposed between adjacent convolutions of said strip and overlying said perforated areas and spaced therefrom inwardly of said cylinder, said baffle members respectively having at their leading sides a lengthwise rib of generally V shape in cross section extending inwardly of said cylinder with its leading side abutting the cylinder wall

and extending therefrom at an inclination in the direction of rotation of said cylinder, said baffle members except for said ribs thereof being substantially concentric with the cylinder wall defining therewith spaces closed at their leading sides and their ends and open at their following sides for free flow of fluid through said spaces and perforated areas while guarding against entry into said spaces of articles under treatment.

2. In a parts treating machine, a rotatably mounted cylinder having a feed end and a discharge end open for discharge of the treated articles, means for rotating said cylinder in one direction, a continuous helical strip seating on and secured to the inner face of said cylinder for the full circumference thereof and disposed to propel articles under treatment toward the discharge end of said cylinder during rotation thereof in said one direction, the wall of said cylinder being provided with perforated areas spaced apart circumferentially thereof, means for supplying treating fluid to said cylinder, and imperforate baffle members overlying said perforated areas spaced inwardly of said cylinder therefrom and respectively having at their leading sides a lengthwise reinforcing rib of substantially V shape in cross section extending inwardly of said cylinder, said baffle members extending between adjacent convolutions of said strip with their ends secured to said adjacent convolutions and their leading sides extended to the cylinder wall and secured thereto providing reinforcement for the latter and for said convolutions of said strip, said baffle members except for said ribs thereof being substantially concentric with the cylinder wall and defining therewith and with the contiguous portions of said adjacent convolutions, spaces closed at their leading sides and ends and open at their following sides for free flow of fluid through said spaces and perforated areas while guarding against entry into said spaces of articles under treatment.

3. In a parts treating machine, a rotatably mounted cylinder having a feed end and a discharge end open for discharge of the treated articles, means for rotating said cylinder in one direction, a continuous helical strip seating on and secured to the inner face of said cylinder for the full circumference thereof and disposed to propel articles under treatment toward the discharge end of said cylinder during rotation thereof in said one direction, the wall of said cylinder being provided with substantially rectangular perforated areas of substantial extent both lengthwise and circumferentially of said cylinder and respectively including a plurality of perforations, said perforated areas being spaced apart circumferentially of said cylinder by intervening substantially rectangular imperforate areas of substantial extent having smooth and unobstructed inner surfaces, means for supplying treating fluid to said cylinder, and imperforate substantially rectangular baffle members secured to the inner face of said cylinder disposed between adjacent convolutions of said strip, said baffle members being substantially coextensive with and overlying said perforated areas in proximity and substantially concentric spaced relation thereto defining therewith spaces closed at their leading sides and ends and open at their following sides for free flow of fluid through said spaces while guarding against entry into said spaces of articles under treatment.
